FEEDING MECHANISM FOR ARTICLES IN SHEET FORM.

No. 819,376.

Specification of Letters Patent.

Patented May 1, 1906.

Application filed June 13, 1904. Serial No. 212,308.

To all whom it may concern:

Be it known that I, STUART H. PRAY, a citizen of the United States, residing at Norwood, in the county of Norfolk, State of Massachusetts, have invented a certain new and useful Improvement in Feeding Mechanisms for Articles in Sheet Form, of which the following is a specification, reference being had therein to the accompanying drawings.

10 The invention relates to mechanism for feeding articles in sheet form from a stack or pile.

It consists in improved mechanism of the said class constructed and operating to relieve the leading or bottom article of the stack or pile from the weight or pressure of the remainder of the latter at the time of the withdrawal of such article and in addition embodying, in combination with the other 20 functional elements thereof, transferring gripper devices of peculiar character and mode of operation.

The features of the invention are adapted to be utilized in the feeding of various articles.

25 For the purpose of conveniently disclosing one manner in which the invention may be reduced to practice I have illustrated the said features embodied in a form of mechanism 30 which I have successfully employed in handling signatures of books—as, for instance, in machines for gathering signatures.

In the drawings, Figure 1 shows in isometric part of the signature-feeding mechanism 35 of a signature-gathering machine. Fig. 2 shows in front elevation one set of the feeding mechanism. Fig. 3 is a view showing the parts of Fig. 2 in elevation from the right-hand side in the latter figure, certain portions of the cams being broken away in order 40 to show parts that otherwise would be hidden. Fig. 4 shows in elevation one of the separators detached. Fig. 5 is a side elevation of the same. Fig. 6 is a view of the same 45 in plan. Fig. 7 shows in front elevation the carrier of one of the transferring-heads. Fig. 8 shows the same in side elevation. Figs. 9 and 10 are views in side and front elevation, respectively, of the under jaw of one of the 50 transferring-heads. Figs. 11 and 12 are similar views of the upper jaw of one of the transferring-heads. Fig. 13 is a side elevation of the gripper-actuating cam of one of the transferring-heads.

Having reference to the drawings, suitable means is provided for supporting conveniently the supplies of signatures or other articles which are to be fed. I contemplate that the said supplies usually shall be arranged in vertical stacks or piles in which the signatures lie horizontally one upon another, although in different cases they may be otherwise arranged. Suitable holders for the said stacks or piles are provided. Any desired form of hopper or other receptacle may be used in practice. In the present instance the machine is shown provided with an elevated shelf 2, Figs. 1 and 3, upon which the stacks or piles of signatures are placed, the said shelf having in connection therewith sets of uprights, as 3 3 and 4, Figs. 1 and 2, to retain in place the respective stacks or piles. Thus for each stack or pile there are provided two opposite uprights 3 3, forming side pieces, and one upright 4, forming a front piece, 75 these three uprights partially inclosing the stack or pile. The side uprights 3 3 are suitably attached to the shelf 2, as by bolts or screws 5 5, adjustment of one of the said side uprights toward and from the other to accommodate signatures of various widths being provided for by means of slots 6 6, Fig. 1, in the table 2, through which slots the stems of the said bolts or screws pass. The front upright 4 is supported by a right-angled bracket 80 7, Fig. 1, having one arm thereof attached to one of the side uprights 3 and having its other arm extended parallel with the front edge of the shelf 2, the said arm supporting the said upright 4 at a short distance from the said 85 front edge of the shelf. The said distance is such as to leave the front portion of the stack or pile unsupported and to enable the head end of the bottom signature in the stack or pile to be depressed at the front of the shelf 90 by means of the devices which hereinafter are described and to permit such signature to be withdrawn from beneath the stack or pile.

By way of affording a clear preliminary understanding of the general character of the essential working parts of my feeding mechanism I first will refer briefly to such parts and their main functions. In connection with each stack or pile of signatures I provide a picker, by means of which to separate the forward portion of the leading element of the stack or pile from the succeeding elements thereof. In the present case the leading ele-

ment of the stack or pile is the bottom or underlying signature in such stack or pile, and the picker is employed to depress the forward portion of the said bottom signature at the 5 front of the forward edge of the shelf 2, thereby carrying it away from the signature next above. Various kinds and constructions of devices suitable for the purpose have been proposed heretofore for use in this and similar 10 connections, and I do not necessarily limit myself in the case of the broader embodiments of the invention with respect to the particular kind or construction of picker which is used or to the precise mode of operation thereof. Preferably, however, I employ a suction or vacuum picker, and I have shown such a picker in the accompanying drawings at 8, Figs. 1, 2, and 3. The forward portion or head end of the leading signature of a stack 15 or pile having been moved away from the corresponding portion of the next succeeding signature by the action of the picker, a separator, as 9, then is caused to enter into the opening thereby produced in order to more 20 completely effect the separation between such portions of the said signatures, and in addition the said separator is caused to act against the said succeeding signature, so as to move the remainder of the stack or pile away 25 from the bottom or leading signature in a manner to relieve the last-mentioned element from the weight or pressure of the remainder of the stack or pile at the time of the withdrawal of the said bottom or leading element, 30 so as thereby to facilitate the said withdrawal. The precise construction, &c., of the separator is not material to the invention. For withdrawing the leading signature from the stack or pile and delivering the same at 35 the required point I employ devices which in some cases may be variously constituted and constructed. Various devices and arrangements for the purpose have heretofore been proposed for use in similar connections, and I 40 do not necessarily limit myself in the case of embodiments of the broader phase of the invention with respect to the particular character or construction of the withdrawing and transferring devices. Preferably, however, I 45 employ moving grippers, and preferably, also, I employ grippers moving in a circular path. In the more complete embodiment of the invention I employ gripper devices of peculiar character and mode of operation which I 50 have shown in the accompanying drawings and presently will proceed to describe.

Having now indicated the general character and main features of the essential working parts of my feeding mechanism, I will proceed to describe the said mechanism more in detail.

The picker 8, which is shown in the drawings, comprises, essentially, a body portion or arm having an air-passage which extends 65 longitudinally through the same, as indicated

by dotted lines in Figs. 2 and 3, the working end of the said body portion or arm having a cup 10 of suitable flexible and elastic material—such, for instance, as rubber. The rear end of the body portion of the picker has connected therewith flexible tubing, as 11, Figs. 2 and 3, leading to suitable suction-producing apparatus, which may be of any approved or usual character and is not necessary to be shown herein. The picker 8 is mounted upon a carrier-bar 12. The said carrier-bar extends transversely with reference to the stack or pile of signatures at the front of the holder or receptacle for the latter. In the case of the illustrated mechanism a plurality or series of holders or receptacles is provided upon the shelf 2, (see Fig. 1,) and the bar 12 extends lengthwise of the said shelf past the said series of holders or receptacles, it constituting a common carrier for the series of pickers which is employed in the said mechanism. To the bar 12 are communicated movements by which the required action of the pickers is secured. The instrumentalities for communicating the proper movements to the bar 12 70 will presently be described. The said movements comprise, in brief, endwise movements of the bar 12, whereby lateral movements of the respective pickers are occasioned from a position at one side of each of the respective 75 stacks or piles to positions in line with the latter and back again and vertical movements whereby the pickers are lifted and depressed.

The separator 9 is essentially L shape in 80 plan, as shown best in Fig. 6, and it comprises, essentially, the bent arm 13, Figs. 4, 5, and 6, by means of which it is attached to the separator-carrying bar, and an extension 14, projecting from the said arm horizontally at 85 right angles to the latter. One end—namely, 90 15—of the working portion of the separator is wedge shape to facilitate the entrance of such end between the signature that has been engaged and partly drawn down by the 95 picker and the next succeeding signature. A thin plate, as 16, is applied to the laterally-projecting portion of the separator for the purpose of affording a broader support to the 100 signature which is above the same.

The separator 9 is mounted upon a carrier-bar 17, which latter, as shown by Figs. 1, 2, and 3, extends lengthwise of the supporting arrangements for the series of stacks or piles of signatures and constitutes a common carrier for the series of separators. To the said carrier-bar are communicated the movements by which the required action of the separators is secured. The instrumentalities for communicating such movements to the 115 120 bar 17 will presently be described. The said movements comprise in brief endwise movements of the bar 17, whereby the lateral movements of the respective separators are occasioned and vertical movements whereby 125 130

the lifting and depressing of the separators are occasioned. The picker-bar 12 and separator-bar 17 are applied to guides which are provided, as at 18, Figs. 1, 2, and 3, in arms 19. A suitable number of the arms 19 is provided in the direction of the length of the machine to support the picker-bar and separator-bar and prevent the same from springing. The arms 19 are pivoted at 20, Figs. 1, 2, and 5 3, to brackets 21, Fig. 3, upon the shelf 2, the pivots 20 of the arms being located at the upper corner of the forward edge of the said shelf, so as to cause the pickers and separators in their vertical swinging movements to 10 move concentrically with such edge. Anti-friction-rolls 22, mounted upon the said arms 19, rest upon the peripheries of cams 23 upon the rotating shaft 24. By the action of the said cams as the main shaft is rotated the 15 arms 19 are swung so as to communicate the necessary vertical movements to the picker-bar and separator-bar. The picker-bar and separator-bar are adapted to move endwise within the guides 18 of the vertically-swinging arms 19. For the purpose of communicating to the picker-bar and separator-bar the necessary endwise movements I employ the cam 25, Fig. 1, which is mounted on the shaft 24. The said cam has cam-grooves 26 20 and 27, receiving studs or cam-rolls 28 29, which, respectively, are mounted upon studs projecting from the collars 30 31. The collar 30 is fast upon a sleeve 32, which latter is fitted to a bearing at 33, that is suitably supported 25 on the machine-framing. At its inner end the said sleeve is formed with collars 34 34, receiving in the space between them a lug 35, projecting from the picker-bar 12. These collars 34 34 coöperating with the lug 35 30 transmit to the picker-bar the endwise movement which is communicated to the sleeve 32 by the action of the cam-groove 26, although leaving the picker-bar free to be swung vertically in an arc concentric with the said sleeve. Within the sleeve 32 is fitted the cylindrical slide-bar 36, it being supported at its outer end in another bearing 37. The said slide-bar has the collar 31 aforesaid attached thereto and also is provided at its inner end 35 with collars 38 38, receiving between them the lug 39, which is attached to the separator-bar 17. These lugs transmit to the separator-bar the endwise movement which is communicated to the slide-bar 36 by the action of the cam-groove 27 upon the stud or roll 29, that is carried by the said slide-bar 36; although leaving the said separator-bar free to swing in a vertical arc in unison with the picker-bar. To prevent rotation of the 40 sleeve 32 and slide-bar 36 under the action of the respective cam-grooves, the said collars 30 and 31 are furnished with flat projections 40 40, working between the parallel guide-surfaces 41 41, which are connected with the 45 bearings 33 37. The axes of the sleeve 32 and slide-bar 36 are in line with the axes of the pivots 20 of the arms 19 by which the picker-bar and separator-bar are carried, and consequently the swinging movements of the said arms do not affect the connection between the said bars and the sleeve and slide-bar. Upon the shaft 24 adjacent each hopper or receptacle for signatures is mounted a transferring-head, of which the grippers hereinbefore referred to constitute the chief essential 70 working element. The grippers are mounted upon an arm or carrier 42, which is made fast upon the shaft 24. The said carrier is shown separately in Figs. 7 and 8. The gripper-jaws are marked, respectively, 43 and 44, Figs. 2, 3, and 9 to 12, the jaw 43 (shown separately in Figs. 9 and 10) being what is referred to hereinafter as the "under" jaw and the jaw 44 (shown separately in Figs. 11 and 12) being what is referred to hereinafter as the "upper" jaw. The jaws 43 and 44, respectively, are mounted upon the pivots 45 and 46, these pivots being located eccentrically with relation to each other—that is to say, at a short distance apart in the direction in which the transferring-head rotates. The pivots at 45, 46 are constituted by studs which are connected with the respective jaws and fitted to bearings at 47, 48, Figs. 2, 3, 7, and 8, respectively, in the carrier- 90 arm 42, the said studs being free to turn in the said bearings. The stud 45 of the under jaw 43 projects beyond its bearings, as shown in Fig. 2, and has applied thereto a spiral spring 49, one end of which is engaged with a fixed portion of the carrier-arm 42, while the other end thereof is engaged with a collar 50, which is made fast upon the stud 45 by means of a clamping-screw 51. By the action of the said spring 49 the under jaw 43 is 100 held pressed forward in its normal position, the said position being determined by the engagement of a projection or lug 52, Figs. 9 and 10, upon the said jaw with the projection or lug 53, Figs. 7 and 8, which is formed or provided upon the carrier-arm 42. The upper jaw 44 is furnished with a pin or roll, as at 54, working in the groove of a cam 55 (shown separately on a reduced scale) in Fig. 13, termed by me the "gripper-operating" cam 110 and mounted in a fixed position surrounding the shaft 24, the said cam being furnished with a suitable projection 56 for attachment to a fixed portion of the machine-framing. The surface 57 at the outer end of the under 115 jaw 43 is the portion of the said jaw which coöperates with the upper jaw 44 in clamping a signature. To the outer end of the upper jaw 44 is attached a plate 58, it projecting at the rear of the said upper jaw toward the under jaw and being adapted to pass over the end of the said under jaw as the upper jaw is moved backward and forward, the under surface of the said plate 58 coacting with the end surface 57 of the under jaw in clamp- 125 130

ing the signature. Adjacent the pivotal mounting for the jaws the carrier 42 is furnished with a segmental support 59 concentric with shaft 24 for the signature which has been drawn out from the adjacent stack or pile by the action of the grippers and during the transfer of the said signature in being delivered.

The operation in general will be clearly understood from the foregoing description. I may add that the signatures in each stack or pile lie with one end of each thereof toward the front of the machine and with the folded back of each at one side of the hopper or receptacle—that is to say, each signature lies with its head end to the front and is folded back to one side. The picker 8 normally occupies a position at one side of the stack or pile with which it coöperates. (See Figs. 1 and 2.) In the present drawings this position is at the right-hand side of the stack. In this position the picker stands normally below the level of the upper surface of the table 2, upon which the signatures rest. (See Fig. 3.) In its action it first is shifted laterally (toward the left in the drawings) from the position of Figs. 1 and 2 into a position beneath the adjacent forward corner of the signature with which it is to engage. It then is raised into engagement with the said corner. Then the air is exhausted from the same to cause the signature to adhere thereto, and then the cup is depressed. At this stage the separator, which previously has occupied a position at the right of the stack or pile with which it coöperates, is moved laterally (toward the left in the drawings) to the position shown in Figs. 1 and 2, and thereby caused to enter between the depressed corner of the bottom signature and the signature which is next above in the stack or pile. Then the vacuum is relieved, and the picker having become disengaged from the signature is returned laterally toward the right in the drawings to its original position (shown in Figs. 1 and 2) out of the path of rotation of the transferring-grippers. The separator now is caused to rise under the action of the grade 231 of the cam 23, thereby lifting the stack or pile which is above the same, so as to take the weight or pressure of the stack or pile off the bottom signature. The separator remains in its lifted position while the gripper-jaws engage with the bottom signature and pull it out from beneath the stack or pile and also while the picker returns into position beneath the stack or pile again. The separator then is withdrawn edgewise laterally from under the stack or pile by movement toward the right. In being depressed by the picker the head end of the bottom signature is bent downward over the free edge of the shelf 2, upon which it rests. The carrying-arms 19 are pivoted at the said front edge of the shelf 2 in order that the pickers and separators

may swing in arcs concentric with that in which the portion of the signature with which they engage is bent. The maximum of clearance thereby is secured in consequence of keeping the surface of the separator approximately parallel with the surface of the signature against which it acts. As the transferring-head rotates and as the grippers thereon come around beneath the stack of signatures and approach the head end of the bottom or leading signature the upper jaw is moved forwardly by the action of its cam 55, thereby separating it from the under jaw and swinging it inwardly toward the shaft 24, so that in its advance with the transferring-head the said jaw shall not strike against the depressed portion of the said bottom or leading signature. The lower jaw accompanies the upper jaw forward until the lower jaw reaches its normal position on the transferer-head, such position being determined by the engagement of the stop-lugs or projections 52 53 with each other. As soon as the upper jaw passes the head end of the bottom signature it is caused by its cam 55 to move rearwardly, its rearward movement being caused to proceed at such relative speed as to cause its plate 58 to overlap the said head end. In its rearward movement the upper jaw by contact with the under jaw transmits corresponding movement to the latter, both continuing to move rearwardly in unison at approximately the same rate of speed as the transferring-head is moving forward. This retains the jaws in a relatively stationary position with respect to the edge of the signature. Meanwhile, in consequence of the fact that the jaws are pivoted upon different centers they close upon each other so as to grip the head ends of the bottom or leading signature between them. Upon the termination of the rearward movement of the upper jaw that is occasioned by the action of the cam 55 the closed jaws move onward with the transferring-head, withdrawing the bottom signature from the stack or pile, the rear portion of the said signature then finding a support on the segment 59 at the rear of the jaws. The signature is then delivered from the transferring-head by the opening of the jaws, which permits the said signature to fall from the latter upon the support 60 in front of the transferring-head. The recess below the plate 16 of the separator 9 alongside the portion 14 of the separator affords clearance to the upper jaw of the transferring-grippers as such jaw is moved into position for engagement with the head portion of the bottom or leading signature.

I claim as my invention—

1. The combination with means for holding a stack of signatures or the like to be fed, and transferring devices to engage with the elements of the said stack successively and withdraw such elements from the stack, of a

- picker, a separator, and actuating connections for said picker and separator whereby the picker is caused to engage the leading element of the stack and whereby the separator is caused to enter between said element and the remainder of the stack and then is moved to relieve the pressure of the said remainder from the said leading element to facilitate the withdrawal of the latter.
- 5 2. The combination with means for holding a stack of signatures or the like to be fed, and transferring devices to engage with the elements of the said stack successively and withdraw such elements from the stack, of a succession-picker, a separator, and actuating connections for said picker and separator whereby the picker is caused to engage the leading element of the stack and whereby the separator is caused to enter between said element and the remainder of the stack and then is moved to relieve the pressure of the said remainder from the said leading element to facilitate the withdrawal of the latter.
- 10 3. The combination with means for holding a stack of signatures or the like to be fed, and transferring-grippers to engage with the elements of the said stack successively and withdraw such elements from the stack, of a picker, a separator, and actuating connections for said picker and separator whereby the picker is caused to engage the leading element of the stack and whereby the separator is caused to enter between said element and the remainder of the stack and then is moved to relieve the pressure of the said remainder from the said leading element to facilitate the withdrawal of the latter.
- 15 4. The combination with a support for a stack of signatures or the like to be fed, a picker, a separator, and actuating connections for said picker and separator whereby the picker is caused to engage the leading element of the stack and whereby the separator is caused to enter between said element and the remainder of the stack, and then is moved to relieve the pressure of the said remainder from the said leading element to facilitate the withdrawal of the latter, of a rotating carrier, two jaws upon said carrier mounted upon pivots which are eccentric with relation to each other, and means whereby in the rotation of the carrier the jaws are moved rearwardly to pass over the forward edge of the said element, and also moved relative to each other to close upon said edge, the continued forward movement of the carrier effecting the withdrawal of the element from the stack.
- 20 5. The combination with a support for a stack of signatures or the like to be fed, a picker, a separator, and actuating connections for said picker and separator whereby the picker is caused to engage the leading element of the stack and whereby the separator is caused to enter between said element and the remainder of the stack and then is moved to relieve the pressure of the said remainder from the said leading element to facilitate the withdrawal of the latter, of a rotating carrier, a movable spring-actuated gripper-jaw mounted on said carrier, an opposing jaw also mounted on said carrier, and a cam whereby in the continued forward rotation of the carrier the latter jaw is actuated to communicate a rearward movement to both jaws, close them upon an edge of the said element, and withdraw the latter from the stack.
- 25 6. The combination with a support for a stack of signatures or the like to be fed, a picker, a separator, and actuating connections for said picker and separator whereby the picker is caused to engage the leading element of the stack and whereby the separator is caused to enter between said element and the remainder of the stack, and then is moved to relieve the pressure of the said remainder from the said leading element to facilitate the withdrawal of the latter, of a rotating carrier, two jaws upon said carrier mounted upon pivots which are eccentric with relation to each other, and means whereby in the rotation of the carrier the jaws are moved rearwardly to pass over the forward edge of the said element, and also moved relative to each other to close upon said edge, the continued forward movement of the carrier effecting the withdrawal of the element from the stack.
- 30 7. The combination with a support for a stack of signatures or the like to be fed, a picker, a separator, and actuating connections for said picker and separator whereby the picker is caused to engage the leading element of the stack and whereby the separator is caused to enter between said element and the remainder of the stack and then is moved to relieve the pressure of the said remainder from the said leading element to facilitate the withdrawal of the latter.
- 35 8. The combination with a support for a stack of signatures or the like to be fed, a picker, a separator, and actuating connections for said picker and separator whereby the picker is caused to engage the leading element of the stack and whereby the separator is caused to enter between said element and the remainder of the stack and then is moved to relieve the pressure of the said remainder from the said leading element to facilitate the withdrawal of the latter.
- 40 9. The combination with a support for a stack of signatures or the like to be fed, a picker, a separator, and actuating connections for said picker and separator whereby the picker is caused to engage the leading element of the stack and whereby the separator is caused to enter between said element and the remainder of the stack, and then is moved to relieve the pressure of the said remainder from the said leading element to facilitate the withdrawal of the latter, of a rotating carrier, two jaws upon said carrier mounted upon pivots which are eccentric with relation to each other, and means whereby in the rotation of the carrier the jaws are moved rearwardly to pass over the forward edge of the said element, and also moved relative to each other to close upon said edge, the continued forward movement of the carrier effecting the withdrawal of the element from the stack.
- 45 10. The combination with a support for a stack of signatures or the like to be fed, a picker, a separator, and actuating connections for said picker and separator whereby the picker is caused to engage the leading element of the stack and whereby the separator is caused to enter between said element and the remainder of the stack, and then is moved to relieve the pressure of the said remainder from the said leading element to facilitate the withdrawal of the latter, of a rotating carrier, two jaws upon said carrier mounted upon pivots which are eccentric with relation to each other, and means whereby in the rotation of the carrier the jaws are moved rearwardly to pass over the forward edge of the said element, and also moved relative to each other to close upon said edge, the continued forward movement of the carrier effecting the withdrawal of the element from the stack.
- 50 11. The combination with a support for a stack of signatures or the like to be fed, a picker, a separator, and actuating connections for said picker and separator whereby the picker is caused to engage the leading element of the stack and whereby the separator is caused to enter between said element and the remainder of the stack, and then is moved to relieve the pressure of the said remainder from the said leading element to facilitate the withdrawal of the latter, of a rotating carrier, two jaws upon said carrier mounted upon pivots which are eccentric with relation to each other, and means whereby in the rotation of the carrier the jaws are moved rearwardly to pass over the forward edge of the said element, and also moved relative to each other to close upon said edge, the continued forward movement of the carrier effecting the withdrawal of the element from the stack.

In testimony whereof I affix my signature in presence of two witnesses.
